UNITED STATES PATENT OFFICE

2,536,688

RANGE CONSTRUCTION

Edwin A. Jones, Webster Groves, and Robert E. Gardiner, University City, Mo., assignors to Majestic Manufacturing Company, St. Louis, Mo., a corporation of Missouri

Application October 30, 1944, Serial No. 560,922

1 Claim. (Cl. 126—1)

1

This invention relates to improvements in a range construction, particularly of the type wherein the fuel employed is either coal or wood.

One object of the invention is a provision of a novel oven and oven surrounding flue arrangement adapted to produce a maximum in heat efficiency. A second object is to provide novel clean-up means whereby removal of accumulated soot is facilitated.

A further object is to provide a novel arrangement in conjunction with a removable ash pan adapted to seal the opening for said pan when the latter is in place, thus obviating the escape of fly ash into the kitchen when shaking the grates.

Other advantages and features of the invention will be noted in the description to follow, reference being had to the drawings which form part of this specification. The specific construction illustrated is a preferred one, which is subject, of course, to modifications within the scope of the appended claim.

In said drawings:

Fig. 1 is a front elevational view of a range embodying my invention;

Fig. 2 is an end elevational view thereof;

Fig. 3 is a rear elevational view thereof;

Fig. 4 is a horizontal sectional view taken approximately on the line 4—4 toward the top of Fig. 1;

Fig. 5 is a similar view on the broken line 5—5 across the middle of Fig. 1;

Fig. 6 is a fragmentary vertical sectional view taken on the lines 6—6 in Figs. 1 and 3;

Fig. 7 is a similar view taken on the lines 7—7 in Figs. 1 and 3;

Fig. 8 is a similar view on the line 8—8 in Fig. 3;

Fig. 9 is a vertical sectional view on the lines 9—9 in Figs. 2 and 4; and

Fig. 10 is a fragmentary side elevational view of an ash pan construction.

The range, generally indicated A, is mounted on and supported by a suitable base B. A conventional oven door C and a fire door D of the concealed hinge type are provided, as are ornamental panels E and F and the usual back guard G.

The interior construction of the range body is such that there is provided a firebox and grate assembly compartment 13, an ash compartment 14 therebelow, an oven or a baking chamber 15, a horizontal flue 16 above the oven, a vertical flue 17 at one side thereof, a horizontal flue 18 beneath the oven, and a vertical flue 19 at the rear of the oven.

2

The compartment 13 is adapted to receive a conventional firebox and grate assembly, generally indicated 20 and outlined in broken lines. This compartment is defined by said grating, the left end of the wall 21 of the range body or casing, the front and rear walls 22 and 23, respectively, of the range body, the cooktop 24, and the upper portion of a vertical wall included in the oven structure to be described hereinafter.

10 The ash compartment 14 is similarly defined with one exception, namely, the substitution of the range body bottom plate 25 for the cooktop 24 in the above description.

As shown in the drawings, the oven is unique 15 in that it is formed by two complementary components, generally designated 26 and 27. The member 26, forming the side and top walls, is of inverted channel-shaped cross section, one vertical side portion 28 thereof forming the left hand 20 wall, the opposite vertical side portion 29 forming the right hand wall, and the connecting or web portion 30 forming the top wall of the oven. The member 26 extends from the front wall 22 of the stove to the rear wall 23 thereof, and the side 25 walls 28 and 29 of the member 26 rest upon the bottom wall 25. The member 27, forming the bottom and rear walls, is L-shaped in cross section, the horizontal portion 31 forming the bottom wall of the oven, and the vertical portion 32 thereof forming the rear wall of said oven. The member 27 is inserted into the member 26, with the bottom wall 31 secured to the side walls 28 and 29 above the bottoms thereof, and with the back wall 32 secured to the side walls 28 and 29, 30 and the top wall 30, but spaced inwardly from the main back panel 23.

The upper horizontal flue 16 is defined by the front and rear casing walls 22 and 23, the top wall 30 of the oven and the cooktop 24. The vertical down-flue 17 at the right end of the range is defined by the front and rear casing walls 22 and 23, the oven side wall 29, and the right hand end casing wall 33.

The lower horizontal flue 18 below the oven is 45 defined by the front and rear walls 22 and 23, the walls 28, 29 and 31 of the oven, and the body bottom 25.

The vertical flue 19 at the rear of the oven is 50 defined by the rear wall 23 of the casing, a portion of the side walls 28 and 29 of the oven, the oven back wall 32, the bottom plate 25, and the cooktop 24.

As shown in the drawings, all of the various 55 casing, oven and flue walls or partitions are provided with flanges whereby they may be spot-

welded, bolted, or otherwise secured to one another to form a rigid, compact structure.

In addition to an oven opening, the front wall 22 is provided with a rectangular opening 34 having an inwardly turned flange 35. This opening is adapted to receive a removable ashpan 36 which extends rearwardly from said opening to a point in the ash compartment 14 adjacent the rear wall 23 of the oven body. The opening 34 is considerably larger than necessary to accommodate the removal and replacement of the ashpan.

A cover plate 37, provided with a handle 38, is of a size large enough to completely seal the opening 34 by engagement with the front wall 22 around the opening. The cover plate 37 is maintained in rigid spaced relation to the front wall 39 of the ashpan by means of a flanged, U-shaped bracket 40, welded or otherwise rigidly secured to the cover plate 37 and to the wall 39. The arrangement is such that a downwardly opening notch 41 (Fig. 10) is formed between the cover plate 37, the front wall 39 of the ashpan, and the bottom of the bracket 40. When the ashpan is in place, the notch 41 is of a size to engage over the bottom 35' of the turned flange portion 35 (Fig. 6). By means of this notch engageable with the flange, the entire ashpan proper is suspended and supported wholly on the flange 35' by the bracket 40 in conjunction with the cover plate 37. In this manner, due to the weight of the ashpan, the cover plate 37 is caused to impinge against the outer face of the front wall 22, thus completely sealing the opening 34 to prevent any possibility of fly ash escaping into the room when shaking the grates. The fire door D may be suitably recessed to accommodate the handle 38. As shown, particularly in Fig. 9, a deflector 42 may be secured to the wall 28 to assist in depositing ashes into the pan.

The rear wall 23 has an opening 43 provided with a suitable draft regulating device 44 disposed below the level of the grates. It also has two vertically spaced openings 45 and 46, both leading into a smoke-box 47 provided with an upstanding flange 48 to support the usual stove pipe 49, shown in broken lines. The opening 46 is provided with a damper 50 operable by means of a handle 51 whereby the opening may be covered or uncovered. An access opening 52 is also provided in said rear wall. This opening is normally closed by means of a removable cover plate 53 provided with a knob.

A cleanout opening 54 is provided as shown in the lower portion of the wall 28. It is also normally closed by a similar cover plate 55. The end wall 29 has formed therein below the bottom of the oven a flue opening 56. A diagonally extending baffle plate 57 in the form of an angle is rigidly secured to the underside of the bottom plate 31 of the oven. It extends in the flue 18 from a point adjacent the rear end of the opening 56 forwardly to a point adjacent the left front corner of the oven, as best seen in Fig. 5. Its depth is such that its lower edge is spaced above the bottom 25.

The cooktop 24 is of conventional construction and is removably supported in a rectangular frame 58 suitably contoured to receive it.

Operation

Assuming now that the range is to be used for cooking purposes only, and that the fuel x, indicated by broken lines in Fig. 9, has been ignited, the operating handle 51 is manipulated to

move the damper 50 to its open or broken line position shown in Fig. 7. Thereupon the hot gases and smoke emanating from the burning fuel are drawn into the smoke-box through the uncovered opening 46. That portion of the cooktop directly above the firebox compartment absorbs most of the heat at this time, as is understood.

Assuming, however, that the range is to be used primarily for baking purposes, the operating handle 51 is manipulated to move the damper 50 to its closed or full line position (Fig. 7). Thereupon the hot gases and smoke emanating from the burning fuel are drawn laterally across the horizontal flue 16, thence downwardly through the flue 17, thence through the opening 56 and laterally and diagonally across approximately one-half of the horizontal flue 18 (see arrows in Figs. 5 and 9). The diagonal path of the products of combustion from the opening 56 to a point adjacent the lower left front corner of the oven is effected by the baffle 57.

The baffle causes the larger part of them to pass around its left hand extremity (see Fig. 5), whence they are drawn rearwardly across the balance of the flue 18, and next upwardly through the vertical flue 19, and by way of the opening 45 into the smoke box 47.

With the above circuitous flue arrangement, it is evident that the entire top wall of the oven, its entire bottom and rear wall, its entire right side wall, and a substantial portion of its left side wall are exposed to, and in a position to, absorb the heat from the products of combustion originating in the firebox.

Thus, uniformity of temperature is had throughout the entire expanse of the oven, a condition conducive to best baking results.

The accumulation of soot in a range of the present type is unavoidable. A novel arrangement to facilitate its removal is embodied in the present construction. By removing the cover plate 53, which is normally held in place by a latch, or in any other suitable manner, access is afforded a conventional scraper to any and all walls defining the vertical flue 19. The dislodged particles of soot come to rest upon the bottom plate 25 of the horizontal flue 18.

The vertical flue 17 has little or no tendency to accumulate soot. The horizontal flue 18, however, does accumulate a considerable amount and requires cleaning from time to time.

To remove the soot in this flue, including that scraped from the flue 19, it is only necessary to remove the ashpan and then the cover plate 55, whereupon a conventional scraper may be inserted through the opening 54 to scrape the soot into the ash compartment. The baffle 57 may be cleaned concurrently. Should the flue 16 require cleaning, the scraper may be inserted for this purpose by removing one or more cooking lids.

Obviously, the embodiment illustrated may be modified in some respects without departing from the scope of the invention.

What is claimed is:

Range construction comprising an ash compartment defined by walls including a front wall, an opening in said front wall for insertion into and removal from said compartment of an ashpan including a lower edge formed as an inwardly directed horizontal flange, an ashpan disposed in said compartment, and means supporting said ashpan in suspended relation in said compartment on said lower edge including a bracket secured to the front end of said ash-

pan above the lower edge thereof and a closure plate for the opening secured to said bracket and depending therebelow, said closure plate being spaced from the front surface of the ash-pan, said bracket resting on said lower flanged edge of said opening with said closure plate biased against the outer surface of the front wall in sealing relation by the weight of said ashpan disposed in said compartment, said ash-pan depending below the said lower flanged edge and bearing against the inwardly directed edge thereof.
